UNITED STATES PATENT OFFICE.

HIRAM A. FRANTZ, OF CHERRYVILLE, PENNSYLVANIA.

ELECTRIC SPARKING MECHANISM FOR EXPLOSIVE-ENGINES.

No. 831,274.

Specification of Letters Patent.

Patented Sept. 18, 1906.

Application filed January 9, 1905, Serial No. 240,133.

To all whom it may concern:

Be it known that I, HIRAM A. FRANTZ, a citizen of the United States, residing in Cherryville, Northampton county, Pennsylvania, have invented certain new and useful Improvements in Electric Sparking Mechanism for Explosive-Engines, of which the following is a specification.

My invention relates to an improved sparking mechanism for explosive-engines, as fully described in connection with the accompanying drawings, illustrating a preferred embodiment thereof, and specifically pointed out in the claims.

Figure 1 is a sectional elevation of a portion of an explosion-engine cylinder, showing my invention applied to the head thereof and indicating the relative arrangement of a piston whose movement is adapted to automatically operate the sparking mechanism at the proper times. Fig. 2 is a partial sectional view taken on the line 2 2 at right angles to that of Fig. 1.

The cylinder 1, provided with the usual water-jacket chamber 2, contains the piston 3, which is represented at about the limit of its upward compression movement and in the act of operating the sparking mechanism. The latter is mounted in the water-jacketed cylinder-head 4 and comprises the adjustably-fixed insulated electrode 5, the electrode-point 6, carried by the pivoted lever 7, and the means for normally maintaining contact between the electrodes excepting at the exactly predetermined moments for sparking and explosion, when such contact is broken by the action of a projecting finger 8 upon the pivoted lever 7 to rock the latter, as indicated, upon its pivotal connection 9 to the cylinder-head. Said finger 8 is adjustably fixed on the piston, so that its extent of projection may be regulated.

The spark-plug 10 screws into the opening 11 in the cylinder-head and is locked in adjusted position by the jam-nut 12. The electrode-stem 5 passes loosely through the central opening 14 of the plug and through insulator-bushings 15 and 16 in the latter and is held in position therein by the jam-nut 17, while its screw-threaded lower end enters the screw-collar 18, abutting midway of the length of the latter with the extension spark-point 19. The circuit-wire 20 is clamped between the jam-nuts 17 and 21 on the stem 5.

The lever 7, which carries at one end the spark-point 6 and is pivoted intermediately

of its length at 9, is closely guided between the extended pivot-ears 22 22, depending from the cylinder-head, so as to be practically in contact with said ears except at its extremities, the purpose of this arrangement being to utilize the water-jacket of the cylinder-head in carrying off from the lever through the contacting ears 22 22 the excessive heat, which is otherwise apt to interfere with proper sparking. To provide for normally holding the electrode-points 19 and 6 in contact, I employ a spring-projected plunger 23 in the cylinder-head, arranged to press upon the opposite end of the lever 7, so as to hold up the spark-point 6 against the point 19 excepting when positively depressed by the finger 8 of the piston striking the opposite end of the lever 7 and raising the latter, together with the spring-depressed plunger 23, thereby rocking the lever and breaking the contact to produce the igniting spark for the compressed charge of gas. The projection of the finger 8 from the piston may be properly regulated, and the electrodes and the tension-spring 24 for plunger 23 may be nicely adjusted, so as to insure the sparking action at exactly the right moment for exploding the charge, and when once properly adjusted the explosions are sure to recur continuously at the proper times.

What I claim is—

1. A sparking mechanism for explosive-engines, comprising in combination with the cylinder-head having a cooling-jacket, a pair of electrodes, a pivoted lever carrying one of said electrodes, means acting on one end of said lever for normally maintaining the electrode at its other end in contact with the other electrode, means for periodically operating said lever to break said contact and ears depending from said cylinder-head and between which said lever is fulcrumed, said ears being approximately in contact with said lever throughout their length and prolonged beyond the fulcrum of the latter and terminating contiguous to the ends of the same, whereby they support and guide said lever and also efficiently transfer thereto the cooling effect of said jacket, substantially as described.

2. A sparking mechanism for explosive-engines comprising, in combination with the engine-cylinder, a sparking plug, an electrode-stem adjustably and insulatedly mounted therein, means for fixing said stem in adjusted position, a screw-collar engaging

the lower end of said stem, an extension spark-point engaged with said collar, an electrode-carrying lever for making contact with said point, means for normally maintaining said contact and means for periodically operating said lever to break said contact.

3. A sparking mechanism for explosive-engines comprising, in combination with the engine cylinder and piston, a sparking plug 10 adjustably mounted in said cylinder, an electrode-stem adjustably and insulatedly mounted in said plug, means for fixing said stem in adjusted position, a screw-collar engaging the lower end of said stem, an extension spark-point engaged with said collar, an electrode-carrying lever for making contact with said point, means acting on said lever for normally maintaining said contact and a finger adjustably fixed to said piston and acting 15 on said lever to periodically break said contact.

4. In combination with the cylinder and piston of an explosive-engine; a sparking mechanism adapted to adjustably determine the sparking moments, said sparking mechanism comprising an adjustable electrode carried by the cylinder and having an extension point, a lever pivoted between its ends and having one of its ends provided with an adjustably-fixed electrode to engage said point, means acting on the other end of said lever for normally maintaining contact between said electrodes, and a finger adjustably fixed to said piston and operating on said lever to break said contact. 35

In testimony whereof I affix my signature in the presence of two witnesses.

HIRAM A. FRANTZ.
